APPARATUS FOR THE REPRODUCTION,
REGULATION, AND CONTROL OF TEMPER-
ATURESWilliam E. Stone, Colonia Anahuac, D. F., Mexi-
co; dedicated to the free use of the People of
the United States of America

Application March 4, 1938, Serial No. 193,846

2 Claims. (Cl. 236—46)

(Granted under the act of March 3, 1883, as
amended April 30, 1928; 370 O. G. 757)

This application is made under the act of March 3, 1883, as amended by the act of April 30, 1928, and the invention herein described and claimed, if patented, may be manufactured and used by or for the Government of the United States for governmental purposes without the payment to me of any royalty thereon.

I hereby dedicate the invention herein described to the free use of the people of the United States of America to take effect on the granting of a patent to me.

This invention relates to an instrument for controlling, regulating, and reproducing temperatures.

One of the objects of this invention is to provide an instrument of the type mentioned that will enable animal and plant life to be subjected in a laboratory to the diurnal variations of habitats, and finds an important use in the study of insect pests, especially fruit flies, existing outside the boundaries of the United States in relation to the possibility of the survival of these flies under variable temperatures to which they may be exposed should they invade the United States.

Another object of this invention is to provide a means for the control of electrically heated cabinets and for processing or conditioning rooms requiring a gradually decreasing rise in temperature for a definite period and a constant temperature thereafter without the use of pressure controls.

Still another object of this invention is to provide an instrument of the type mentioned which will enable determination of developments of insects under constant temperatures in contrast to variable temperatures, of which the constant temperature in any particular case represents the mean.

A further object of this invention is to provide a means for the control of variable temperatures during a definite period, according to a prearranged plan of gradual rise or fall in temperature charted on a recorder as a straight line, or a gradual decrease of rise or fall in temperature charted in the form of a curve.

A still further object of this invention is to produce an instrument of the type mentioned that is inexpensive, of simple construction and which may be easily adjusted to reproduce records from any type of daily or weekly drum temperature recorder or temperature pattern.

Another and still further object of this invention is to provide an instrument of the type mentioned which is portable so that it can be quickly

transferred from one operating location to another.

The following description, considered together with the accompanying drawings, will disclose this invention more fully, its construction and operation of parts, and further objects and advantages thereof will be apparent.

In the drawings:

Figure 1 is a side elevational view of this invention in one of its forms.

Figure 2 is a plan view of Figure 1.

Figure 3 is an end view of Figure 1.

Figure 4 is an end view of Figure 1 opposite to that of Figure 3.

Referring with more particularity to the drawings in which like numerals designate like parts, a cylinder 1 rotatively responsive to a motivating unit (not shown) disposed therein, is vertically mounted on the base 2 of the instrument and may be of any of the ordinary types in general use on thermographs, such as the clock type. This cylinder is adapted to have disposed about its lateral surface a fiber-board chart pattern 3 of approximately 1 millimeter, or slightly less, in thickness, and is attached in the manner 25 of an ordinary thermograph chart. In the drawings this fiber-board chart is shown mounted on the cylinder 1 and held in place by means of a removable band 4.

A vertical shaft 5 is fixedly mounted to the base of the instrument substantially as shown, and carries a horizontal supporting plate 6 adjustably fixed to said shaft by means of a collar 7 and set screw 8. Pairs of vertical brackets 9, 9 and 10, 10 are secured in the manner shown. The brackets 9, 9 support an adjustable tracing arm 11, fulcrumed between said brackets on a threaded horizontal shaft 12 by means of simple point and socket bearings 13, 13. Being mounted on the threaded shaft 12 said tracing arm is made laterally adjustable. Said tracing arm is also adjustable in length, being composed of two parts fitted together by means of a slot 14 and set screws 15, 15. At the outer end of said tracing arm, a tracing point 16 of steel wire, or any other suitable material, is attached by means of a connecting wrist 17 and is designed to follow the contour of the chart pattern 3.

In a manner similar to that of the tracing arm 11, a lever 18 is fulcrumed between the brackets 10, 10. The longer arm of this lever extends upward and is secured to a segmental arc 19 of approximately 115 degrees, substantially as shown. At the upper end of this segmental arc a wire 20 is attached, preferably No. 38 insulated 55

5 copper magneto wire, but any other suitable wire may be employed, and is designed to fall in registry with a fine groove 21, extending the entire length of the arc segment in the middle of its periphery. The other end of this wire carries a weighted platinum pointed contact drop 22 extending to a mechanically actuatable thermostat 23.

10 The tracing arm 11 and the lever 18 are mechanically linked by means of a main adjustment rod 24 and a minor adjustment rod 25. One end of the rod 24 is fixed to the arm 11 at a point between its ends; the other end being pivoted to one end of the rod 25. The other end 15 of said rod 25 is pivoted to the short arm of the lever 18, substantially as shown. Both of said rods 24 and 25 are made adjustable in length by means of threaded spacers 26 and 27, set in threaded sockets 28, 28 and 29, 29. One-half of each of the spacers 26 and 27 are threaded in one direction, and the other half in the opposite direction. In order to delicately balance this instrument, a counter-weight 30 is adjustably mounted on the bearing shaft of the lever 18 by 20 means of a collar 31. Balancing the instrument in this way makes it kinematically constrained.

25 A vertical guide bar 32 is fixed to a lever 33, which lever has a handle 34 and is pivotally mounted at the base of the instrument near the cylinder 1. The object of this guide bar is to hold the point of the tracer arm 11 in proper operating position with respect to the edge of the fiber-board pattern 3.

30 Threaded legs 35, 35, 35, 35 are provided for 35 the purpose of making placement adjustments for the instrument.

35 The operation of this invention is as follows: The chart pattern 3 is prepared and secured about the cylinder 1 in the manner shown in the drawings and above described. The instrument is then adjusted for the particular pattern, the initial adjustment consisting of lengthening or shortening the tracing arm 11 so that the arc described by the tracing point, when in motion, 40 is of the same radius as the temperature arcs on the chart pattern. The movable stage is then raised or lowered until the arc described by the tracing point and the temperature arc of the chart pattern exactly coincide at a point at the 45 front and center of the chart pattern. The last adjustment consists of lengthening or shortening the main adjustment rod 24 until the distance traversed by the contact drop 22 as a result of the movement of the tracer point 16 through the 50 number of degrees represented by the chart pattern 3 is equivalent to the rise and fall of mer-

cury in the thermostat tube (not shown) for an equal number of degrees. The minor adjustment rod 25 is used only when great changes in the operating range of the instrument are desired, and its function is to rectify the position of the 5 arc segment 19 so that maximum range of operation may be maintained under all adjustments. The motivating clock (not shown) of the cylinder 1 is then regulated so that it rotates said cylinder slightly faster than the recorder clock to allow 10 for the thickness of the fiber-board pattern. The tracing point is then rested on the top edge of the fiber-board pattern and as the clock rotates, it follows the pattern raising or lowering the tracing arm. Said tracing arm actuates the rod 15 24, which in turn actuates the rod 25 and consequently the arc segment 19. Thus the drop contact is raised or lowered with the movement of the tracing point. The usual means of a relay equipped with a mercoil contactor may be 20 employed to turn the heat on and off.

Having thus described my invention, I claim:

1. A device for use in the reproduction and control of temperatures comprising a vertically disposed cylinder actuatable by means of a clock 25 mechanism, an adjustable tracing arm vertically mounted between brackets on a vertically adjustable plate, a pointer carried by said arm adapted to rest on and be responsive to the edge of a fiber-board pattern wrapped around said 30 cylinder, a lever fulcrumed between additional brackets on said vertically adjustable plate having a long arm extending upward and a short arm extending downward, a segmental arc of substantially 115 degrees having a longitudinally 35 grooved periphery secured at the end of the long arm of said lever, a weighted contact drop of a thermostat suspended from the upper end of said segmental arc on an electrically insulated wire, adjustable mechanical means connecting said 40 tracing arm and the shorter arm of said lever, and means for mechanically balancing the instrument.

2. A device of the character described comprising a cylinder actuatable by a clock mechanism, 45 a tracing arm, a pointer carried by said arm responsive to the edge of a fiber-board pattern wrapped around said cylinder, a lever having one arm linked to said tracing arm, a segmental arc secured to the other arm of said lever, and a 50 weighted contact drop of a thermostat suspended from the upper end of said segmental arc, whereby said weighted contact drop is responsive to the movements of said pointer.
